Primary Examiner — Michael A. Pratt(74) *Attorney, Agent, or Firm* — Honigman LLP(57) **CLAIM**

I claim the ornamental design for a clamp, as shown and described.

DESCRIPTION

FIG. 1 is a front perspective view of a clamp showing my new design;

FIG. 2 is a front view of the clamp of FIG. 1;

FIG. 3 is a rear view of the clamp of FIG. 1;

FIG. 4 is a right side view of the clamp of FIG. 1;

FIG. 5 is a left side view of the clamp of FIG. 1;

FIG. 6 is a top view of the clamp of FIG. 1; and,

FIG. 7 is a bottom view of the clamp of FIG. 1.

Broken lines in the drawing views show portions of the clamp that form no part of the claimed design.
